COMBINED ENTRANCE WAY ENCLOSURE
AND CANOPY

Lee Strauch, 17-33 160th St., Whitestone, N.Y.

Filed Oct. 29, 1964, Ser. No. 82,383

Term of patent 14 years

(Cl. D13—1)

Fig. 1.

Fig. 2.

Fig. 3.

FIGURE 1 is a top perspective view of a combined entrance way enclosure and canopy, showing my new design, according to one form of the invention;

FIG. 2 is a side elevational view thereof;

FIG. 3 is a top plan view thereof;

FIG. 4 is a top perspective view of the invention according to a modified form thereof;

FIG. 5 is a side elevational view thereof;

FIG. 6 is a top plan view thereof;

I claim:

The ornamental design for a combined entrance way enclosure and canopy, substantially as shown and described.
